OTHER PUBLICATIONS

Jun. 19, 2018—(WO) ISR & WO—App. No. PCT/US18/021546.
(Continued)*Primary Examiner* — Brandon M Rosati(74) *Attorney, Agent, or Firm* — Banner & Witcoff, Ltd.(57) **CLAIM**

The ornamental design for a bag, as shown and described.

DESCRIPTION

FIG. 1 is a top, front, right perspective view of a bag showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is a top, front, right perspective view of an alternative claimed configuration of a BAG showing out new design. The broken lines represent stitching. The broken lines immediately adjacent to the shaded area represent unclaimed boundaries of the design.
